Attorney

UNITED STATES PATENT OFFICE.

BERNARD LIBERMAN, OF PHILADELPHIA, PENNSYLVANIA.

CIGAR BUNCHING.

Application filed March 29, 1922. Serial No. 547,671.

To all whom it may concern:

Be it known that I, BERNARD LIBERMAN, a citizen of the United States, residing at Philadelphia, in the county of Philadelphia,

5 State of Pennsylvania, have invented a new and useful method and means for Cigar Bunching, of which the following is a specification.

10 The invention relates to improvements in cigar bunching. The object is to provide improved method and means for delivering accurately measured charges of scrap tobacco from a source of supply, such as a hopper, to the usual bunching apron of a 15 bunch rolling table.

The special purpose of the invention is to improve the efficiency and accuracy of measuring the charge, and then separating said charge cleanly and effectively, from the 20 mass in the supply hopper from which the charge is received; so that said charge, accurately measured and cleanly separated, is delivered to the bunching apron, or to the intermediate means for conveying said 25 charge to said apron. This invention includes improved method and means for introducing the scrap to the measuring pocket, and improved means for severing any portion of tobacco which may project from 30 the measuring pocket into the hopper, as the margin, for example the edge 16, of said pocket passes the cooperating margin or edge 28 of the hopper.

This invention comprises improvements 35 in the method and means described in my co-pending application Serial No. 515,446 filed Nov. 16, 1921.

Referring to the drawings, which illustrate merely by way of example suitable 40 means for effecting my invention—

Fig. 1 is a plan view of the measuring element.

Fig. 2 is a cross-section on line 2—2 of Fig. 1.

45 Fig. 3 is a perspective view of the shearing member or knife.

Fig. 4 is a vertical cross-section of said measuring element, a portion of the hopper and associated parts, the measuring element 50 in the receiving position.

Fig. 5 is a similar view, the measuring element in the discharging position.

Fig. 6 is a similar but more fragmentary section, showing member 7 in an intermediate 55 position.

Fig. 6^a is a similar fragmentary section

showing member 7 in a still different position.

Fig. 7 is a view in perspective of member 24.

Similar numerals refer to similar parts throughout the several views.

The measuring element comprises the cylindrical body 7, mounted on the shafts or axles 8, and having a reciprocating rotative movement to and from the receiving and discharging positions. This body 7 is provided with the measuring pocket 9 having one wall inclined to the axis of body 7. This pocket 9 is provided with an adjustable plate or wall 10 operated by the adjusting screw 10' for adjusting the depth of the pocket, all of which is clearly described in a co-pending application, and forms no part of this application. On the side wall 75 of the pocket 9 which is inclined to the axis, is provided the cutting member or knife 11, securely fastened to said wall by the screws 12 projecting through slots 13. These screws 12 are reached, when it is desired to 80 move the same, by means of a screw driver inserted through openings 14, normally closed by the screws or threaded plugs 15.

The knife 11 has a sharp cutting edge 16 on its pocket side, which cutting edge should 85 preferably extend a very slight distance above or beyond the true periphery of the cylindrical body 7. This knife or cutting member 11 is also provided in its bottom face or edge with two threaded openings 17, 90 for receiving the adjusting screws 18.

The lower part of the hopper 19 is provided at one lower margin with the arc lip 20 for cooperating with the solid circumferential part of member 7. A part of the 95 opposite lower margin of hopper 19 is cut away, as at 21, thereby providing an opening conforming in width to that of the pocket 9. Beneath the opening 21 in hopper 19 is provided the member 24 having 100 a reverse curve formation 25 from the opening 21 downwardly to a point on the periphery of cylinder 7. This member 24 is preferably bolted to the underside of hopper 19. This forms a recess or pocket 26, 105 corresponding in width to the width of pocket 9, for the purpose hereinafter described. Upon the underside of the member 24 is provided the knife or cutting member 27, having a cutting edge 28 110 adapted to cooperate with the cutting edge 16 of knife or cutting member 11, which is

secured to the inclined wall of pocket 9. The knife 27 is adjustably secured to the member 24 by means of screws 29 in slots 30.

In operation.

When the member 7 is in the position shown in Fig. 4, pocket 9 is entirely open to the hopper 19 which provides the supply of moist scrap tobacco. This scrap will naturally fall into the pocket 9 and fill the same. As the tobacco is moist however its movement is somewhat sluggish and not always uniform, so that the charge in pocket 9, while the same remains in the position shown in Fig. 4, may vary in amount and density. This condition however is corrected in the following operation. As the member 7 moves from the position shown in Fig. 4 to the position shown in Fig. 6, it will be noted that the pocket 9 now registers with a pocket or offset-recess 26 extending downwardly from the main part of hopper 19. This pocket or recess 26 corresponds in width with the pocket 9 and is provided with a curved and inclined wall 25 facing the pocket 9. All of the communicating space of recess 26 and pocket 9 is filled with scrap tobacco in a more or less loose condition. The result of this construction and arrangement is, that as the pocket 9 moves from position, Fig. 6, to position, Fig. 5, the scrap tobacco in said combined space tends to move with pocket 9, and the part in engagement with wall 25 tends to slip along said inclined wall toward the pocket. This results in pressing with gradually increasing pressure, the greater part of the scrap contained in said recess 26, into the pocket 9 by the time the knife edge 16 cooperates with the knife edge 28, and any remnant of scrap projecting beyond the pocket between said knife edges, as they come together, is sheared off cleanly, so that a clean cut uniform charge, of even density throughout its bulk, is brought to or slightly beyond the position shown in Fig. 5.

In moving in the counterclockwise direction slightly past the position shown in Fig. 5, the member 7 comes to a stop and the charge of scrap is discharged from pocket 9 into trough 31.

In the return movement of member 7, in the clockwise direction, it will be noted that pocket 9 is open to recess 26 and also to the space outside the hopper, as indicated in Fig. 6^a. The movement however of member 7, which is capable of about sixteen discharge movements per minute, is of sufficient speed to prevent any of the comparatively slow moving scrap which passes from recess 26 into pocket 9, from escaping from pocket 9 before the margin 32 passes knife edge 28, so that no scrap is discharged from pocket 9 during said return movement of member 7. On the other hand said move-

ment of pocket 9 toward recess 26 facilitates the movement of the scrap into said pocket, so that, by the time the pocket reaches the position, Fig. 4, the pocket is well filled with scrap in comparatively loose formation. In a copending application I have shown means, operating in the hopper just over the pocket, for cooperating in the filling and packing action; but the final filling and packing action is secured by the recess 26 and the wall formation 25, above described.

The shearing operation.

In view of the fact that the scrap tobacco is quite moist, the particles of tobacco leaf are very soft, and the tendency is, where a margin of the pocket engages a margin of the hopper, to crush the particles of tobacco projecting between said coacting margins. This is liable to result in undesirable conditions, such as mashing the soft tobacco and thereby causing a clogging in the vicinity of said coacting margins. I have found it most important therefore to provide means for securing a clean shearing action between said coacting margins so that any particles projecting between said margins, as the same come together and pass each other, shall be cleanly sheared off and not crushed so as to clog and jam the machine. In order to secure this result it is necessary that the coacting knife edges besides operating the one at an angle with the other, be sharp and perfectly adjusted, so that their coaction shall be a true shearing one. For this purpose I provide means for adjusting the knife 11 in the pocket 9. This comprises the set-screws 18, threaded into the lower edge of knife member 11. The slots 13, through which the screws 12 project, provide a considerable leeway for such adjustment, and also permit regrinding the knife edge from time to time as required. This is obviously a distinct advantage over devices of this type, where the knife used is not adjustable, since a single nicking or damaging of the knife edge 16 will render the whole knife useless. With the combined adjustment of the knife 11 and knife 27, it is now possible to secure and maintain a perfect shearing coaction between the two, equal to the action of a pair of well made shears.

What I claim is:—

1. In a scrap bunching machine, the combination of means forming a measuring pocket, movable to and from receiving and discharging positions, means for delivering scrap tobacco thereto, a knife forming a margin of the pocket, means for adjusting the position of said knife, a second knife secured to a stationary part for cooperating with the first knife for shearing off scrap projecting from the pocket.

2. In a scrap bunching machine, the combination of means forming a measuring pocket, movable to and from receiving and discharging positions, means for delivering 45
5 scrap tobacco thereto, a knife forming a margin of the pocket, means for adjusting the position of said knife, a second knife secured to a stationary part for cooperating with the first knife, said knives arranged
10 so that one will coact with the other along its extension but at an angle thereto. 50
3. In a scrap bunching machine, the combination of means forming a measuring pocket, movable to and from receiving 55
15 and discharging positions, means for delivering scrap tobacco thereto, a knife forming a margin of the pocket, means for adjusting the position of said knife, a second knife adjustably secured to a stationary
20 part for cooperating with the first knife for shearing off scrap projecting from the pocket. 60
4. In a scrap bunching machine, the combination of means forming a measuring pocket, movable to and from receiving and discharging positions, means for delivering scrap tobacco thereto, a knife forming a margin of the pocket extending at an angle to the axis of the measuring pocket movement, means for adjusting the position of 65
25 said knife, a second knife secured to a stationary part for cooperating with the first knife for shearing off scrap projecting from the pocket. 70
5. In a scrap bunching machine, the combination of means forming a measuring pocket, movable to and from receiving and discharging positions, means for delivering scrap tobacco thereto, a knife forming a margin of the pocket, means comprising 75
30 set screws threaded therein for adjusting the position of said knife, a second knife secured to a stationary part for cooperating with the first knife for shearing off scrap projecting from the pocket. 80
- secured to a stationary part for cooperating with the first knife for shearing off scrap projecting from the pocket. 85
6. In a scrap bunching machine, the combination of means forming a measuring pocket, movable to and from receiving and discharging positions, means for delivering scrap tobacco thereto, a knife forming a margin of the pocket, means for adjusting the position of said knife, means for securing the knife to the side of the pocket in any position of adjustment, a second knife secured to a stationary part for cooperating with the first knife for shearing off scrap projecting from the pocket. 90
7. In a scrap bunching machine, the combination of means forming a measuring pocket, comprising a rotatably mounted cylindrical body, a knife secured to one wall of the pocket by means of screws operating in slots, said knife having an edge forming one margin of the pocket, said cylindrical body provided with openings through its outer wall to the pocket and in line with said screws, and threaded closures therefor. 95
8. In a scrap bunching machine, the combination of means forming a measuring pocket, movable to and from receiving and discharging positions, a hopper for delivering scrap thereto, means forming an offset recess at the hopper base having a wall converging toward the pocket providing means whereby the scrap in the offset recess is 100
10 pressed into the pocket as the pocket moves toward the discharging position, a knife on the margin of the offset recess and a knife forming a margin of the pocket, said knives being relatively adjustable and adapted to 105
15 cooperate to cut off scrap projecting from the pocket. 110
